DESIGN FOR AN ANTENNA COUNTERPOISE

Arnold B. Bailey, New York, N. Y., assignor to Bell Telephone Laboratories, Incorporated, New York, N. Y., a corporation of New York

Application April 15, 1937, Serial No. 68,799

Term of patent 14 years

To all whom it may concern:

Be it known that I, Arnold B. Bailey, a citizen of the United States of America, residing at New York, in the county of New York and State of New York, have invented a new, original, and ornamental Design for an Antenna Counterpoise, of which the following is a specification, reference being had to the accompanying drawing, forming a part thereof.

The single drawing figure is a perspective view of an antenna counterpoise showing my new design, the two upper cylindrical portions being an antenna, the element immediately below said antenna being an insulator and the lowest cylindrical portion, having a greater diameter than the antenna, being the counterpoise.

I claim:

The ornamental design for an antenna counterpoise, as shown and described.

ARNOLD B. BAILEY.
